THERMOSTATIC ELECTRIC SWITCH AND
CONTACT STRUCTURE THEREFOR

John D. Bolesky, Attleboro, Mass., assignor, by
mesne assignments, to Metals & Controls Cor-
poration, Attleboro, Mass., a corporation of
Massachusetts

Application November 22, 1935, Serial No. 51,034

4 Claims. (CL. 200—138)

This invention relates to thermostatic electric switches and contact structures therefor, and with regard to certain more specific features, to switches, including the contact structure, where-
5 in a more effective make and break of a circuit is accomplished.

Among the several objects of the invention may be noted the provision of a switch, and contact structure therefor, of the class described, 10 wherein a more complete and effective separation of contacts is secured upon opening the switch; the provision of a switch and contact structure therefor, wherein provision is made for more rapidly cooling the contacting elements of the 15 heat generated therein by the making and breaking of circuits therewith; and the provision of a switch and contact structure of the class described which is relatively simple and economical to manufacture. Other objects will be in part obvious and in part pointed out hereinafter.

The invention accordingly comprises the elements and combinations of elements, features of construction, and arrangements of parts which will be exemplified in the structures hereinafter described, and the scope of the application of 25 which will be indicated in the following claims.

In the accompanying drawing, in which are illustrated several of various possible embodiments of the invention,

30 Fig. 1 is a plan view, partially broken away, of a thermostatic electric switch embodying the present invention;

Fig. 2 is a plan view of one form of contact element;

35 Fig. 3 is an end elevation of the contact element of Fig. 2;

Fig. 4 is a side elevation of the contact element of Fig. 2;

40 Fig. 5 is a plan view of a second contact element;

Fig. 6 is an end elevation of the contact element of Fig. 5;

45 Fig. 7 is a cross section taken substantially along line 7—7 of Fig. 1, and illustrating the switch in closed position; and,

Fig. 8 is a cross section similar to Fig. 7, illustrating the switch in open position.

Similar reference characters indicate corresponding parts throughout the several views of 50 the drawing.

This invention is in the nature of an improvement on the thermostatic electric switch, and the contacts embodied therein, as shown in L. K. Marshall Patent 1,700,172, dated January 29, 1929.

55 The general association of elements is quite simi-

lar to that of the said Marshall patent, the improvement lying more particularly in the particular contact structure provided in the present invention.

Referring now more particularly to Fig. 1, numeral 1 indicates a base portion comprising a substantially circular metal member upon which is positioned a circular disc 2 of a suitable insulating material, such as mica. A plurality of contact members 3, 4, 5, and 6, which are described in greater detail hereinafter, are held in the upper surface of the insulating disc 2 by suitable means, such as rivets 7 and 8.

Numerical 9 indicates a thermostatic disc which is of the type disclosed in Spencer Patent 1,448,240, dated March 13, 1923. The disc 9 is supported on the circular base plate 1 by means of a stud 10 (see also Fig. 7) threaded therein. On the stud 10 are threaded, first, a collar 11 having an outwardly extending flange 12, and second, a nut 13. A central hole or opening 14 in the disc 9 fits on the collar 11 and is held in position between the flange 12 and the lower face of nut 13. The arrangement is such that the disc is firmly held but permitted sufficient play to permit it to snap between its opposite positions of concavity in response to ambient temperature changes.

Also threaded into the base 1 are one or more pillars or posts 15, which extend upwardly through suitable openings 16 in the disc 9. The engagement of the posts 15 and openings 16 prevent the disc 9 from rotating on the stud 10 relative to the base 1.

A plurality of contact bridging members 17 are secured to the thermostatic disc in spaced positions adjacent to the periphery thereof in such positions that they will operatively engage the adjacent end portions of pairs of the respective fixed contact members 3, 4, 5, and 6, respectively. Since the particular structure of the movable contacts 17 form no part of the present invention, they will be described only generally. Numeral 18 indicates a rivet which passes through the disc 9. It is insulated from the disc 9 by mica washers 19. Numeral 20 indicates a washer formed with a spherical surface 21, which is secured on the rivet 18 on the under side of the disc 9. At the lower end of the rivet 18, there is loosely held a disc 22 of good contact metal, such as silver.

It is with the construction of the fixed contact members 3, 4, 5, and 6 that the present invention is most particularly concerned. In prior switches of this general type, such as that shown in the

aforesaid Marshall patent, the analogous fixed contact members were stamped from flat sheets of metal and had no projections extending out from their flatness. This meant that they laid flat against the base member 1 in assembly. Their respective ends which constitute the active contact-engaging faces for the movable contacts 17, were thus positioned at such an angle with respect to the movable contact member 22 that there was, particularly during the switch opening operation, a tendency for the movable contacts 22 to lift first from one side of the fixed contacts only to achieve a complete separation by lifting the other side. This sequence was not such as to produce the most advantageous form of break between the contacts; in certain instances, regardless of the speed with which the movable contact 22 was moved, there was a tendency, due to the irregular manner in which the movable contact separated from the fixed contact, to cause arcing, whereby the contacts, both fixed and movable, were unduly heated and corroded.

The difficulty with such completely flat, fixed contacts is solved in the present invention by providing the fixed contact pieces 3, 4, 5, and 6, and more particularly their contact-engaging ends, with faces or portions that are upset or stamped from the main flat plane of the contact. This arrangement is indicated in Figures 2, 3 and 4, with respect to the fixed contact elements 3 and 4 which are relatively long and have contact engaging faces on each end thereof. Referring to Fig. 2, numeral 23 designates the so-shaped contact engaging end portions. Figures 3 and 4 show how these are formed from the main body of the contact 4. The contact 4 may be considered, roughly, as a peripheral segment of a circle or an annular segment. The contact-engaging ends 23 are so formed as to slope upwardly and outwardly, away from the assumed center of the segment. Considered in another light, the main body of the contact 3 is a portion of a flat disc while the ends 23 are portions of a cone or sphere having its center on the same line as the center of the disc.

While the contact portion 3 has been referred to as "flat", by reference to Fig. 4, it will be seen that it is in reality slightly arched. This slight arching is for the purpose of more effectively securing the contact member 4 to the base plate 1, by providing tension in the rivets 7. When the contact element 3 is removed from the base 1 it has the said slight arching, but when it is mounted on the base 1, it is flattened out into a completely flat position.

Contact members 5 and 6 which constitute the terminal pieces of the switch, are short pieces relative to contact members 3 and 4. They are illustrated more particularly in Figs. 5 and 6. They have contact engaging faces 23 on but one end thereof, but these faces 23 are sloped in the same manner as the faces of the contact members 3 and 4.

In the case of the contact members 3 and 4, two rivets 7 are provided for each such contact member. This means that there can be no doubt of their proper angular positioning on the base plate 1. However, in the case of the contact members 5 and 6, there is but one rivet 8 provided, and in order to make sure that the angular position of the contact members 5 and 6 is correct, the rivets 8 therefore are of polygonal (hexagonal, for example) cross section. A correspondingly polygonal opening 25 is formed in each of the contact members 5 and 6. The opening 26 (see Fig. 7) in the base plate 1 is likewise polygonal so that

when the polygonal rivet 8 is used to secure the contact elements 5 and 6 to the base plate 1, there is no doubt of their correct angular positioning.

The manner in which the sloping faces 23 of the fixed contact members of the present invention are more advantageous is indicated in Figures 7 and 8. In Figure 8, for example, the switch is in open position. It will be seen that the movable contact button 22 naturally assumes a position which is almost exactly parallel to the position of the sloping faces 23 of the fixed contacts. When the disc 9 snaps to the circuit-closed position, the inertia of the button 22 is such that it is maintained in substantially the same position shown in Figure 8 even though that involves an angular shifting of the position of the rivet 8 with respect to the button 22. This means that the movable contact button 22 and the fixed contact 23 are brought together in parallel relationship and touch each other over the entire engaging surfaces at practically the identical instant. Figure 7 shows the contact-closed position.

On the other hand, when the disc 9 snaps back from the Fig. 7 to the Fig. 8 position, opening the circuit, the same condition prevails and inertia holds the movable contact button 22 in substantially the same angular position. Thus, the button 22 moves away from the fixed contact 23 maintaining its parallel relation thereto, and a complete and uniform separation is obtained over the entire contact area at the same instant.

These advantageous conditions in the making and breaking operations are not to be obtained with the completely flat fixed contacts of the aforesaid Marshall patent structure, for example.

Another considerable advantage of the fixed contact structure of the present invention is that the contacting regions or surfaces 23 are all displaced to a small, but measurable extent from the surfaces of the mica disc 2. This leaves a space which is indicated in Figure 7 for example, by numeral 27. Into this space 27, the ambient medium such as air, may readily circulate. This circulation of air aids in effecting a quick cooling of the contact surfaces if they have become heated. In other words, the fixed contact of the present invention provides for the circulation of air therearound and thus can cool off much more quickly than the fixed contacts of the aforesaid Marshall structure, for example, where the air can effectively reach only one surface (the upper surface) of the fixed contact. This cooling effect is of course advantageous.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. In a thermostatic electric switch, a base member, a snap acting thermostatic disc mounted thereon at its center, said snap acting disc carrying at least one movable contact member at its periphery, and at least one fixed contact member mounted on said base in position to cooperate with said movable contact member, said fixed contact member having a contact engaging face sloped at an angle to the surface of the base member, said sloped portion sloping away from the point of mounting of said disc.

2. In a thermostatic electric switch, a base member, a snap acting thermostatic disc mounted thereon at its center, said snap acting disc carrying a plurality of movable contact members at its periphery, and a plurality of fixed contact members mounted on said base in position to cooperate with said movable contact members, said fixed contact members having a contact engaging face substantially conforming to an imaginary cone surface the apex of which is in line with the point of mounting of said disc.

3. A fixed contact member for switches of the class described comprising a substantially flat piece roughly shaped as a segment of an annulus,

at least one end of said piece being provided with a face sloping with respect to the surface of the remainder of the piece, said sloping face sloping away from the center of the annulus of which the contact is a segment.

4. A fixed contact member for switches of the class described comprising a substantially flat piece roughly shaped as a segment of an annulus, at least one end of said piece being provided with a face sloping with respect to the surface of the remainder of the piece, said sloping face sloping in a direction upwardly and away from the center of the annulus of which the contact is a segment.

JOHN D. BOLESKY.
